SOUVENIR PAPERWEIGHT OR SIMILAR ARTICLE

John F. Berardo, 8727½ La Tijera Blvd.,
Arcadia, Calif. 90045

Filed Sept. 9, 1968, Ser. No. 13,456

Term of patent 14 years

Int. Cl. D19—02

U.S. Cl. D74—12

FIG. 1 is a top view of a souvenir paperweight or similar article embodying my new design;

FIG. 2 is a side view thereof;

FIG. 3 is a front view thereof; and

FIG. 4 is a back view thereof.

I claim:

The ornamental design for a souvenir paperweight or similar article, substantially as shown.
